UNITED STATES PATENT OFFICE.

JOHN BEVERLEY MACLAUGHLIN, OF OTTAWA, ONTARIO, CANADA.

BOOT OR SHOE.

1,074,127.

Specification of Letters Patent. Patented Sept. 30, 1913.

Application filed February 17, 1913. Serial No. 749,009.

To all whom it may concern:

Be it known that I, JOHN BEVERLEY MACLAUGHLIN, a subject of the King of Great Britain, and resident of the city of Ottawa, 5 Province of Ontario, Dominion of Canada, have invented certain new and useful Improvements in Boots or Shoes, of which the following is the specification.

This invention relates to improvements in 10 boots or shoes and the objects are to give elasticity of step to the wearer, to reduce the fatigue of walking and also to ventilate the interior of the shoe, and it consists essentially of a movable inner sole, 15 spring supported at the heel and adapted to assist in lifting the heel of the wearer during the operation of walking.

In the drawings, Figure 1 is a sectional view through the shoe. Figs. 2 and 3 show 20 perspective views of the bottom and top connecting plates for the spring.

Referring to the drawings, A represents a boot or shoe, B the outer sole thereof and C the heel.

25 D represents the inner sole which is loose within the shoe and which, if desired, may only extend part way down from the heel. In accordance with this invention, this inner sole is normally maintained in slightly 30 raised position above the heel by means of a stiff spiral compression spring 10 located in a recess 11 in the heel, the downward movement being limited by a block 12 on the underside of the movable sole adapted 35 to engage a shoulder 13 in the recess 11. It may be found desirable, instead of leaving the spring loosely in the recess 11, to provide connecting plates 14 and 15 at the top and bottom respectively, which are connected to the block 12 and the bottom of 40 the heel respectively, the said plates having means by which the end of the spring may be engaged therewith. As illustrated, the top plate 15 is formed with an aperture

16 in which the ends of the spring may be 45 received and a groove or recess 17 to receive and snugly hold the end of the spring. The bottom plate 15 is provided with a corresponding aperture 18 and recess or groove 19. 50

It will be seen that in operation each time the weight of the wearer is thrown on the ball of the foot, the heel will be raised by means of the spring 10. When the weight is thrown on the heel the spring 55 will be compressed. This gives a very desirable elasticity of step and the movement of the sole D serves to ventilate the interior of the shoe.

As many changes could be made in the 60 above construction and many apparently widely different embodiments of my invention, within the scope of the claim, constructed without departing from the spirit or scope thereof, it is intended that all matter contained in the accompanying specification and drawings shall be interpreted 65 as illustrative and not in a limiting sense.

What I claim as my invention is:—

A boot or shoe having a recess in the heel 70 thereof, a loose inner sole, a spring in the recess, a top plate having a recess and formed with an aperture through which the end of the spring may extend, and a groove or recess adapted to fit and snugly hold the 75 end of the spring, a bottom plate provided with a corresponding recess and aperture through which the end of the spring may extend, and a recess or groove adapted to snugly receive and fit a portion of the 80 spring.

In witness whereof I have hereunto set my hand in the presence of two witnesses.

JOHN BEVERLEY MACLAUGHLIN.
